US00D333794S

United States Patent [19]

Emori

[11] Patent Number: Des. 333,794

[45] Date of Patent: ** Mar. 9, 1993

[54] COATING THICKNESS TESTER

[75] Inventor: Motohiko Emori, Tokyo, Japan

[73] Assignee: Kett Electric Laboratory, Tokyo, Japan

[**] Term: 14 Years

[21] Appl. No.: 534,417

[22] Filed: Jun. 7, 1990

[30] Foreign Application Priority Data

Feb. 28, 1990 [JP] Japan 2-6153

[52] U.S. Cl. D10/70; D10/72

[58] Field of Search D10/70, 72; 33/755-765; 324/229, 230; 364/563

[57] CLAIM

The ornamental design for a coating thickness tester, as shown.

DESCRIPTION

FIG. 1 is a front elevational view of coating thickness tester showing my new design;

FIG. 2 is a rear elevational view;

FIG. 3 is a top plan view;

FIG. 4 is a bottom plan view;

FIG. 5 is a left side elevational view;

FIG. 6 is a right side elevational view; and,

FIG. 7 is a front, top and right side perspective view thereof.

FIG. 1

FIG. 2

FIG. 3

FIG. 4

FIG. 5

FIG. 6

FIG. 7
